UNITED STATES PATENT OFFICE.

JOHN FEKETE, OF BRIDGEPORT, CONNECTICUT.

VALVE-GRINDER.

1,135,677.

Specification of Letters Patent. Patented Apr. 13, 1915.

Application filed January 19, 1915. Serial No. 3,037.

To all whom it may concern:

Be it known that I, JOHN FEKETE, a citizen of the United States, and resident of Bridgeport, in the county of Fairfield and State of Connecticut, have invented certain new and useful Improvements in Valve-Grinders, of which the following is a specification.

My invention relates to new and useful 10 improvements in valve grinding tools such as are used for grinding puppet valves and valve seats of gasoline automobile motors, but is also obviously adapted to be used for other purposes.

15 The object of the invention is to provide a grinding tool which will impart an oscillatory movement to a valve, similar to that produced in hand grinding; further to provide a tool for the above purpose which may 20 be oscillated through the medium of a handle and by a backward and forward movement of the lever by the operator; further to construct the parts so that a comparatively slow backward and forward movement of the operating lever will produce a 25 more rapid oscillatory movement of the valve upon its seat; further to construct the device in a simple and inexpensive way so as to permit of its being manufactured comparatively inexpensively thus permitting it 30 to be sold at a moderate price, and finally to design the tool so that it will not take up very much room above the valve to be ground and whereby the hand movement required to produce the operative movement 35 of the tool can be arranged off to one side where most available for operative purposes.

With these and other objects in view the 40 invention resides and consists in the construction and novel combination and arrangement of parts hereinafter more fully described, illustrated in the accompanying drawings, and pointed out in the claim here- 45 to appended, it being understood that various changes in the form, proportion, size and minor details of construction within the scope of the claim may be resorted to without departure from the spirit or sacrificing any of the advantages of the inven- 50 tion.

Similar characters of reference denote like or corresponding parts throughout the several figures of the accompanying drawings forming a part of this specification and 55 upon which—

Figure 1 shows a side elevation of my improved valve grinding tool complete with screw driver blade attached, and one hand of an operator indicated in dotted lines as 60 supporting the tool. Fig. 2 shows a central vertical section throughout the body and operative portions of the tool, illustrating the spindle bearing, lever pivot and head. Fig. 3 is a bottom plan view of the valve 65 grinding tool as shown in Fig. 1 and Fig. 4 is a detached perspective view of a screw driver blade such as is shown attached to the tool in Fig. 1 and for engaging a puppet valve.

Referring in detail to the characters of reference marked upon the drawings 6 represents the body portion of the valve grinding tool, 7 the handle and 8 an extended portion of the body. An upwardly disposed 75 lug 9 is formed upon the outer end of the extension in a manner to form an additional means of engaging the tool.

In practice my improved tool would be held by one hand of the operator, in the 80 manner indicated by dotted lines in Fig. 1, wherein I have attempted to show the handle portion of the tool resting in the palm of a hand and the lug 9 engaged between the thumb and forefinger thus forming a rigid 85 grasp of the tool in the hands of the operator.

The handle portion of the body is provided with a central longitudinal bore 10 therethrough in which one end portion 11 of a spindle is journaled. A screw 12 which is seated in the top of the handle serves to threadably engage this end of the spindle in a way to hold it in position. A small pinion 13 is formed intermediate of the 90 length of the spindle and also forms a shoulder that operates against the under side of the body. The lower end portion 14 of the spindle (see Fig. 3) is provided with a transverse slot 15 to receive the screw driver 100 blade 16 shown in Figs. 1 and 4 and which obviously serves as the means for engaging

the slot in the top of the puppet valve before mentioned.

A head 17 is detachably secured to the lower spindle end 14 and is provided upon its under side with a pair of extended pins 18 which further serve for the engagement of some forms of puppet valves.

An operating lever 19 is pivotally connected to the underside of the extension 8 at the point 20 in a manner to be swung backward and forward. The short end portion of this lever is provided with a segment of a gear 21 that alines and meshes with the pinion 13 of the spindle before mentioned. The outer end of this lever is provided with a handle 22 by means of which the lever may be thrown backward and forward and thus rocked upon its pivot in a way to oscillate the pinion and its spindle at a comparatively rapid rate of movement. When the head is connected by means of the blade 16 to a puppet valve the latter would obviously be operated and oscillate in a manner to grind it to its seat as desired.

Having thus described my invention what

I claim and desire to secure by Letters Patent is:—

In a valve grinder of the class described, the combination of a body portion including an upwardly extended handle and lug, a spindle having a pinion formed intermediate of its length one portion of the said spindle being journaled in the said handle, a head detachably secured to the other end of the spindle and having a transverse blade slot formed therein, extended pins seated in the under face of the outer portion of the head, a lever pivoted to the lug end of the body and having a segment upon its short end to engage the pinion and a handle upon its longer end to operate the lever, pinion and head.

Signed at Bridgeport in the county of Fairfield and State of Connecticut this 16 day of Jan. A. D., 1915.

JOHN FEKETE.
